(57) **CLAIM**

The ornamental design for a vehicle mountable cooking platform, as shown and described.

DESCRIPTION

FIG. 1 is a top perspective view of a vehicle mountable cooking platform embodying our new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings illustrate portions of the vehicle mountable cooking platform that form no part of the claimed design.
